COLOR PLATE AND PRINTING FORM
REGISTERING MACHINE

Emil Bruno Beccard, St. Louis, Mo.

Application October 5, 1939, Serial No. 297,987

2 Claims. (Cl. 33—184.5)

This invention relates to certain new and useful improvements in color plate and printing form registering machines the peculiarities of which will be hereinafter fully described and 5 claimed.

More particularly this invention relates to a device for registering color plates and printing forms used by the printing and lithographing industry and allied affiliates and the main objects 10 of my invention are to provide means first, for accurately locating on each of a series of lithographs or printing forms enclosed in separate frames, the position of each portion of the color plate or printing form so that superposed color 15 portions will accurately register to form the finished impression and desired color; second, to provide such a device that will receive and hold uniformly the separate frames or chases and contained color plate forms and accurately indicate 20 the position of the respective color portions to assist the printer in accurately locating the superposed color portions to make the finished color plate and printing; third, to facilitate the adjustment of the indicating points and their 25 respective positions defining said color portions or printing forms; fourth, to facilitate the removal of the indicating points and their adjustable carrier blocks on their respective supporting bars, from the supporting posts and platen over which 30 they are adjustably located; fifth, for holding the supporting bars of the carrier blocks rigidly in their proper adjusted positions yet allow removal and accurate replacement of the bars and their 35 indicating points after such adjustment in regard to said color portions; and other objects and features of construction hereinafter described and claimed.

In color printing it is desirable to accurately 40 locate different colors in the design being made and in which a foundation color is superposed by another color to make the desired tint or shade in the finished design. When the separate impressions are successively made, great care is necessary 45 that they register accurately and such registration ordinarily requires time and care to attain.

My device not only attains accurate registration 50 of the color portions of the design, but greatly reduces the time previously required and thereby reduces the cost of the finished product and increases the output and profit in producing the finished color plate in practically perfect condition.

55 In the accompanying drawing in which like

reference numerals indicate corresponding parts:

Fig. 1 represents a perspective view in isometric projection of a bed plate having upstanding corner posts supporting longitudinal parallel bars arranged in staggered position at different 5 heights, and transverse bars thereon having slidably adjustable blocks provided with depending pins by which the positions of color portions in a frame mounted on the bed plate are located;

Fig. 2, a transverse central sectional elevation 10 on 2—2 of Fig. 1;

Fig. 3, an enlarged detail in vertical section on line 3—3 of Fig. 2, showing a portion of an indicating pin adjustably mounted in its carrier block 15 which is slidably mounted on its transverse supporting bar; and

Fig. 4, an enlarged plan view of the end of a longitudinal guiding bar for one end of a transverse pin-supporting bar.

Referring to the drawing, the numeral 1 designates a rectangular bed plate having at its corners upstanding posts 2—2' forming opposing pairs at the sides of said bed plate. Both pairs of the posts are provided on their opposing faces with U-shaped projections 3, arranged at different 20 heights in a staggered series, each projection 3 being located successively further from the central longitudinal vertical plane in ascending order so that each lower projection in posts 2 and its corresponding projection in post 2', are a shorter 25 distance apart than the next projection above, and the successive pairs of projections above in the staggered series are similarly spaced.

These U-shaped or other projections form 30 supports for parallel longitudinal bars connecting the opposing posts 2—2 at one side of the bed plate.

The posts 2—2' on the opposite side of the bed plate are provided on their opposing faces 40 with similar staggered projections located respectively in horizontal planes through the corresponding projections on the opposite posts 2—2. Longitudinal bars are carried in said projections 3 and are readily lifted from their supporting projections by the preferred staggered arrangement providing successively wider distance apart in ascending direction of the projections 3 from the opposing pair 2—2 at one side 45 of the bed plate, and the corresponding pair 2'—2' at the other side of the bed plate as shown in Fig. 1.

The said longitudinal bars are preferably different; the bars 4 connecting the posts 2—2 at one side being preferably round rods supported in 55

corresponding opposing projections 3 on the posts 2—2, while the longitudinal bars 5 at the opposite side of the plate have round ends 5', Fig. 4, similarly fitting the respective projections from 5 the posts 2'—2', but having rectangular intermediate portions and each provided with a groove 6 in the upper face to serve as a guide for a wheel 7 mounted on a journal end 8 of a connecting transverse bar 9 which has on its opposite end a notch 10 on its underside or otherwise fitting on the respective side bar 4 and temporarily secured in its adjusted position by a thumb screw 11 mounted in the respective bar 4, or otherwise clamped.

15 The wheel 7 fits snugly in the guiding notch 6 of its bar 5 as indicated in Fig. 2 and tends to maintain the adjacent end of the transverse bar at right angles to the bar 5 in any adjusted position of the transverse bar connecting the 20 respective pair of side bars as shown in Fig. 1 and Fig. 2.

Thus each transverse bar 9 has one end detachably engaged to its longitudinal bar 5 by wheel and groove engagement or other suitable 25 engagement, while its opposite end is slidably adjustable on the adjacent longitudinal bar 4 and is provided with thumb screw or other clamping 30 device by which its engagement can be fixed to its bar 4, so that the bar 4, clamped to the transverse bar 9 can be lifted out of the U-shaped 35 projections on the posts 2—2 and the bars remain clamped together. The wheel and groove of the opposite end of the bar are preferably disengaged leaving the bar 5 in position. The journal ends 5' allow the bar 5 to turn slightly when such disengagement is effected, and such slight rotation of the bar 5 facilitates 40 disengagement of the wheel from its groove; other suitable detachable engagement instead of the wheel and groove connection may be used. Each bar 9 has a block 12 slidably mounted thereon and provided with a thumb screw 13 or other suitable clamping means to fix it temporarily in its adjusted position on its trans- 45 verse bar 9.

Vertically mounted in said sliding block is a pin 14 threaded or otherwise adapted for vertical adjustment of its lower point with regard to the corner or other distinctive portion of a 50 color plate or printing form 15 that is adjustable in and then is firmly secured in, a chase or frame 16 disposed on the bed plate to which said frame is fastened by screws 18 or otherwise, and said form is firmly secured by wedges 17 or 55 otherwise after adjustment, as indicated in Fig. 2.

The chase and its contained form thus become a unit and all points on the form are fixed relative to the screws 18 holding the chase to 60 the bed plate.

The points of the pins 14 can be then brought adjacent to corners or other distinctive points of the color portions on the form by sliding the transverse bars on the longitudinal bars and 65 respectively adjusting their sliding blocks 12 thereon. The points of the pins are then adjusted vertically into close proximity to the distinctive points of the color plate by adjusting them downward in their threaded connection 70 with the carrier blocks (see Fig. 1). When such adjustment is completed the respective bars 4 are clamped to the adjacent ends of the transverse bars by the thumb screws 11 or otherwise, and then the bars 4 and the respective trans- 75 verse bars 9 can be readily lifted in their clamped

together condition from the projections 3 supporting the bars 4, while the opposite end of the transverse bars can be disengaged from the bars 5 on the other side of the bed plate which are preferably left in position on their supports. 5

The screws 18 holding the chase and its contained form to the bed plate, are then removed and the chase and form as fixed within it are placed on a suitable press and fastened by screws thereto ready for printing the first color of the 10 design.

Another chase and form is then fastened to the bed plate by the screws 18 and one or more of the pins with their connected transverse and longitudinal bars are then replaced and their 15 indicating points are thus located in the same position as they were first located with regard to the first form. This second form is then shifted so that the pin points will be located over the same portions by which they were positioned 20 in the first form, by moving the form in its chase till its position is identical, relative to the pin points, as was the first form. The wedges 17, or other fastening means, then securely fasten this second form in its chase so that one or more 25 of the pins are again located over corresponding portions of the design.

One or more other portions are likewise defined by superposing other pin points respectively adjusted over other color portions as above 30 described, and thus a portion or portions of the design that are to receive the second color are indicated. The bars are then removed as previously described, and this second form and its chase are removed from the bed plate, and transferred to the printing press on which it will be secured by the screws 18 or other fastening means that will locate the second form for printing the second color of the proposed design in exactly the relative positions of the color portions 35 to the color previously impressed.

A third or successive color portion is located in a similar manner by fastening a third chase to the bed plate, replacing the bars in their supporting projections and thus relocating the 45 pin points for indicating the preceding colors in the same positions in the air as before. This third form is then shifted in the chase until the previously adjusted pin points are located over the identical portions they define in their previous 50 adjustments. The wedges or other fastening means then firmly secure the form in its chase and make the chase and its contained form a unit as previously described. The third color portions being then defined by adjusting other 55 pin points over definite portions of the form from which the third color will be printed, the bars and their points are removed as before, allowing this third chase and its form to be taken from the bed plate and mounted in the printing 60 press for printing the desired third color which will be accurately impressed in its proper relation to the other parts of the design, and any danger of overlapping or misprinting of this 65 third color is avoided.

The vertical adjustment of the pins allows them to be raised slightly from the form while the form is being adjusted and thus avoids scratching the form. Then the pin points are lowered to their exact position to locate the 70 form accurately.

One end of the transverse bars is reduced or tapered at 19 to facilitate mounting the carrier blocks on their respective transverse bars.

The carrier blocks support the pins offset at 75

one side of the respective transverse bar as shown in Fig. 1, and the blocks may be reversed upon the transverse bar as shown in Fig. 1, so that two pins can be located a comparatively short distance apart when such is required by the color in the design in the form below.

Thus it will be understood from the above description, that any reasonable number of colors or portions of a printing form can be designated 10 by a multiple number of pins suitably adjusted with regard to definite portions of the design, and then successive forms and their respective chases can be successively positioned on the bed plate and the forms shifted to accord with the points 15 previously fixed so that each form will print accurately its respective color after its transfer to the printing press for such purpose.

The size of my device and the number of bars is shown for illustration only, as it is evident that 20 the size of said device may be provided according to the size of the chase and its enclosed form which in some cases may be relatively larger than shown in the illustrations. The holes in the bed plate and the screws 18 are located identically 25 with those in the printing press and thus locate in the press the color portions for the respective color, in the same relative position as the other color portions on the other forms in their respectively enclosing chase. It is evident that 30 such accuracy is obtained by my device that cannot be obtained otherwise except by an expenditure of much more time and effort than is required in the use of my device.

The different lengths of the transverse bars 35 carrying the pins with indicating points, facilitate the removal of the transverse bars and the longitudinal bars to which they are clamped. Such differences of length also facilitate replacement of the several bars in their former position 40 so as to bring the indicating points in the same position as before, and thus allow shifting the succeeding color plates or forms within their respective chases which have been fastened to the bed plate and thus definitely locate on each form 45 in identical positions, the indicating points previously defining the prior forms. Then one or more points are positioned over portions of the form which are to receive another color for printing the finished design and thus provide for obtaining 50 the accuracy of all the color portions successively printed.

To recapitulate, in color printing a set of separate forms each adapted to print an individual color in the design are loosely mounted in their individual frames and after the frames are fixed to the bed plate by the screws 18 or otherwise, each is then adjusted in its frame to accord with the previously positioned indicating pin points, 55 that indicate the previous color or colors on the prior forms. For example, the form for printing the first or foundation color of the design is wedged in its frame that has been screwed to the bed plate. Then some of the pin points are positioned over definite points of the first color 60 portion of the form thus fixed in its frame and the position of this first color portion is indicated by the pin points which thus show the relative position of this foundation color portion to the 65 fastening screws of the frame; the pin points being then clamped in said position on their supporting bars, can be lifted with their clamped together bars from above the form which is then readily removed from the bed plate and transferred to the printing press on which then it

is fixed by the screws or other fastening means in its operative position.

Another form of the set together with its frame in which it is loosely mounted, is then placed on the bed plate and then fastening means for its frame secures the frame to the bed plate; then the bars with their indicating pins relatively clamped thereto, are replaced in their supports and the pin points assume the same position as on the first form by which they were located. 10 The second form is then shifted in its frame till the indicating points are positioned over the same color portion by which they were located over the first form. This second form having been thus adjusted by means of the indicating 15 pin points, it is wedged in its frame and becomes a unit with it. Other pin points are then adjusted over other different points of another color portion and are clamped in such indicating position similarly to the pin points indicating the 20 foundation or prior color portion.

The second color portion being thus indicated with regard to the first color portion and likewise to the screws fastening its frame to the bed plate, its form and chase can be removed from 25 the bed plate after the pin points and their supporting bars have been lifted off, and this second frame and its form fixed therein, can be placed on the printing press and secured thereto in the same position as the prior frames and 30 forms. Such identical positions successively of the set of forms that may be required for the multiple colors, insures that each color successively impressed in making the design, will be accurately located in its correct position without 35 overlapping or otherwise making an inaccurate assembling of the various color portions in the design.

It is therefore plain that each chase or frame is identically placed with regard to the screws or 40 means for fastening or locking the frame successively on a printing press, but that each form differs by having the portion of its surface that prints the respective color in a raised position relative to the other color portions so as to receive the appropriate color thereon; and that 45 by shifting each form in its frame when the latter is fixed on the bed plate, so that the raised portion of each successive form is located by the previously adjusted indicating pin points over 50 prior portions of the design, the said raised portion of each succeeding form is located in its proper relative position in its frame and then wedged in said position, that thereby it is positioned accurately with respect to the other portions, so that when the form with its frame is 55 transferred to the printing press and locked or secured thereon in a position identical with that of prior forms from which the colors have been printed, that the succeeding color impression will 60 be accurately located or registered on the design being printed.

I do not confine myself to the exact construction above described, except by the appended 65 claims.

I claim:

1. A color plate and printing form registering machine comprising a bed plate having four posts in two pairs on respective sides, said posts having two series of projections on the opposing faces of each pair respectively arranged staggered in opposite lateral directions increasing the horizontal distance between the two series in succession upward, longitudinal bars supported by 70 said projections, transverse bars adjustably car- 75

ried by said longitudinal bars, clamping means to secure one end of each transverse bar to its adjacent longitudinal bar, vertically disposed pins adjustably carried on the transverse bars, and means to fix the lower indicating points of said pins in their adjusted indicating positions to allow removal with their supports and replacement to restore the points of said pins to their former indicating positions.

2. A color plate and printing form registering machine as in claim 1, said projections being U-shaped for lifting out in succession said longitudinal bars and their transverse bars respectively clamped thereto, and for replacing them again in their former position. 5

EMIL BRUNO BECCARD.
